beyond the arc struck on the radius b . The edge 7 lies in the plane of the shoulder seat 6 and preferably, though not necessarily, extends between the points of convergence of the ends of 5 the arcs struck on the radii a and b with the straight edges of the shoulder seat 6. Such disposition of the chordal edge 7 affords a relatively wide bearing seat 8 at each corner of the pot.

It has been explained that it is disadvantageous 10 to increase the weight of annealing pots. Furthermore, it will be apparent that in order to afford the enlarged bearing seats 8 it is only necessary to increase the area in the plane of the shoulder seat 6. Hence the front surface of the 15 excess metal at each corner, in the form of a wall 9, extends from the chordal edge 7 toward the adjacent portions of the inner wall of the pot. The outline of the wall 9, as best shown in Fig. 4, is preferably substantially triangular and the apex 20 thereof is arranged to converge with the inner wall of the pot well above the median point in the vertical extension thereof.

Thus a shelf-like portion is provided at each 25 corner of the pot and provides an extension of the bearing seat at each corner. These shelf-like portions are thus provided by pads confined to the upper edge at each corner of the pot and I thereby attain the advantage of enlarged bearing seats without substantially increasing the weight of the pot.

While I have illustrated and described a preferred embodiment of my invention it is to be understood that this is capable of variation and modification and I therefore do not wish to be limited to the precise details set forth but desire 5 to avail myself of such changes and alterations as fall within the purview of the following claim.

I claim:

An annealing pot including corner portions each having a substantially horizontal ledge and said ledges providing seats on which another annealing pot may be stacked, each of said corner portions including an excess metal portion arranged on the inner side of the pot and extending throughout at least a substantial portion of the 15 vertical height of the same, an arc defined by the inner surface of each of said excess metal portions lying radially inwardly of and relative to an arc formed by the junction of the inner surfaces of the adjacent intersecting side walls of the 20 pot, each of said ledges including an inner surface having an upper edge extending as a chord relative to a circle including said arc and between the inner surfaces of said side walls, and the inner surface of each of said ledges being tapered 25 downwardly and outwardly from its upper edge to its lower end.
